CLAIM

The ornamental design for a combined electronics tray and container, as shown and described.

DESCRIPTION

FIG. 1 is a top perspective view of a combined electronics tray and container according to the present invention;
FIG. 2 is a front view of the combined electronics tray and container according to the present invention;
FIG. 3 is a rear view of the combined electronics tray and container according to the present invention;
FIG. 4 is a left side view of the combined electronics tray and container according to the present invention;
FIG. 5 is a right side view of the combined electronics tray and container according to the present invention;
FIG. 6 is a top view of the combined electronics tray and container according to the present invention; and,
FIG. 7 is a bottom view of the combined electronics tray and container according to the present invention.

The broken lines shown in the drawings are for the purpose of illustrating portions of the combined electronics tray and container that form no part of the claimed design.

1 Claim, 5 Drawing Sheets
